United States Patent Office

Des. 176,878
Patented Feb. 7, 1956

176,878

CLOCK

Paul Irene Nicolas, Paris, France, assignor to Jaz. S. A.,
Paris, France, a corporation of France

Application January 27, 1955, Serial No. 34,271

Claims priority, application France November 18, 1954

Term of patent 7 years

(Cl. D42—7)

FIG. 1.

FIG. 2.

FIG. 3.

FIG. 4.

Fig. 1 is a front perspective view of a clock with the sliding doors in an open position, showing my new design;

Fig. 2 is a front perspective view thereof with the sliding doors in a closed position;

Fig. 3 is a side elevational view; and

Fig. 4 is a rear elevational view.

The dominant features of my design reside in the portions shown in full lines.

I claim:

The ornamental design for a clock, substantially as shown and described.
